UNITED STATES PATENT OFFICE.

BARTON S. SNOW, OF BATAVIA, ILLINOIS, ASSIGNOR TO T. W. SNOW CONSTRUCTION CO., OF CHICAGO, ILLINOIS, A CORPORATION OF ILLINOIS.

DRYING APPARATUS.

Application filed April 14, 1922. Serial No. 552,683.

To all whom it may concern:

Be it known that I, BARTON S. SNOW, a citizen of the United States, residing at Batavia, in the county of Kane and State 5 of Illinois, have invented a new and useful Improvement in Drying Apparatus, of which the following is a specification.

My invention relates, more particularly, to apparatus for drying sand, though I do 10 not wish to be understood as intending to limit it to such material.

My primary object is to provide an improved construction of drier, for sand and other material, which will be rendered more 15 efficient, more economical of operation and be capable of a larger output of dried material than structures of this general character as hitherto provided.

Referring to the accompanying drawings:

Figure 1 is a view in side elevation of a drying apparatus constructed in accordance with my invention. Figure 2 is a longitudinal sectional elevational view taken at a 25 line midway between the sides of the apparatus. Figure 3 is a section taken at the line 3—3 on Fig. 1 and viewed in the direction of the arrow. Figure 4 is a plan section taken at the line 4—4 on Fig. 2 and viewed in the direction of the arrow. Figure 5 is a cross-sectional view taken 30 through a side portion of the apparatus at the line 5—5 on Fig. 1 and viewed in the direction of the arrows and showing one 35 of the similar doors controlling the discharge of gravel from the receptacle into which the wet sand is introduced, and the means for controlling the position occupied by the doors, the doors being shown closed; 40 and Figure 6, a view like Fig. 5 showing the door in open condition.

The structure shown comprises a furnace represented generally at 7, the upper, open end thereof, through which the products of 45 combustion pass, opening through the bottom wall of a substantially horizontally-extending flue 8, at the forward end of the latter, this flue being shown as supported at one end upon the furnace 7 and at its rear 50 end upon a frame represented generally at 9. The flue 8 is of general triangular shape in cross-section, as represented and presenting the upwardly-converging walls 10. The rear end of the flue 8 opens, at its upper 55 portion, at an opening indicated at 11, into

the rear end of a substantially horizontally-disposed flue 12 extending lengthwise of the flue 8 and terminating at its forward end in an upwardly-extending portion 13 forming an outlet for the products of combustion which pass from the furnace 7 through the flue 8, thence to the flue 12 and forwardly through the latter to the point of discharge, the flue 12 being preferably vertically spaced from the flue 8 as represented in Fig. 2.

Surmounting the flue 8 is a receptacle 14 for receiving the sand to be dried, this receptacle being shown as provided with the upwardly-diverging side walls 15 and extending vertically above the flue 12. The bottom of the receptacle 14 is of grid form and comprises the grid sections 16 located above, and at opposite sides of, the walls 10 and in spaced relation to the latter, and 70 the upwardly-extending grid sections 17 which are located at opposite sides of the flue 12 and in spaced relation thereto and the upper extremities of which, represented at 18, converge upwardly, the part of the 75 grid structure formed of the portions 18 being capped by an angle-plate 19. The grid structure described, which extends the full length of the flue 8, is of a form, as 80 shown, presenting slots which extend in a 85 direction crosswise of the flue 8, the grid structure referred to serving as a means for retaining the sand in the receptacle 14 until it has become dried as hereinafter 90 described, whereupon it falls out of the receptacle 14 through the openings provided by the grid. The walls 15 contain in their lower edges openings 20 which are controlled by swinging doors 21 hinged at their 95 upper edges, as represented at 22, to the upper edges of the openings 20, these doors being each formed with an inwardly-extending flange 23 which extends, when the doors 21 are in closed position, closely adjacent the lower extremities of the portions 16 of the 100 grid and effectually prevent the discharge of material therethrough, the portions of the walls 15 between the openings 20 and which are formed of downwardly-extending brackets 24 secured to the solid portion of the walls 15, having inwardly-extending portions 25 which extend closely adjacent the lower edges of the portions 16 of the grid, as shown more particularly in Figs. 105 5 and 6.

The apparatus also involves a lower casing structure 26 the side walls of which, represented at 27, are located at opposite sides of the flue 8 and diverge upwardly, the 5 upper extremities of these side walls being secured, as by the rivets 28, to the outer surfaces of extensions 29 provided on the brackets 24 and spacing the walls 27 from the doors 21 when the latter are in closed 10 position represented in Fig. 5. The bracket extensions 29 present recesses 30 adapted to receive bars 31 which when laid flatwise in these recesses serve to hold the doors 21 closed, and when displaced and turned edge- 15 wise permit these doors to swing to the desired open position represented in Fig. 6.

The bottom of the casing 26, which latter is open at its rear end as represented at 32, inclines downwardly from the front end 20 of the apparatus and extends around the sides and rear wall of the furnace 7 as represented, forming a chute into which the sand and gravel after being dried, discharge. Located at the rear end of the apparatus, and in a position to receive the material discharging from the casing 26 at its open end 32, is a pipe 33, the upper, open, end of which, represented at 34, is widely flaring and so disposed, as shown, that the 30 material discharging through the outlet 32 will be received and guided into the pipe 33 for discharge to any desired point.

The opening in the end wall of the casing through which the flue 12 extends, this 35 opening being represented at 35, is of such area that an annular space is provided which opens into a pipe 36 connected with the end wall referred to and surrounding, in spaced relation thereto, the portion of the 40 flue 12 extending outwardly beyond this wall whereby discharge for the moist air in the enclosure afforded between the portions of the grid, is provided.

The operation of the apparatus is as follows: The sand to be dried is charged into 45 the receptacle 14, preferably to fill the latter and thus extend against all of the exposed portion of the grid, the openings in which are of such size that the sand, in wet 50 condition, is prevented from dropping therethrough.

Assuming the furnace 7 to be operating, the products of combustion in passing 55 through the flues 8 and 12 and radiating heat therefrom, dries the sand which extends in contact with the grid and as the sand dries it drops through the grid, falling upon the outer surfaces of the flues 12 and 8, running down the sides of the latter 60 and discharging into the casing 26, and thence to the pipe 33. The gravel, or other bodies which may be contained in the sand and which are too large to pass through the 65 openings in the grid, upon becoming dried, gravitate along the surfaces of the grid on

the inside of the receptacle 14, and, as desired, are permitted to discharge from the receptacle 14 into the casing 27 by the operator displacing the bars 31 to the position shown in Fig. 6.

It will be understood from the foregoing that the grating, or grid, prevents the wet sand from contacting with the hot wall of the heat flues 8 and 12 and thereby avoids burning out the latter, and the spacing of 75 the grid from the flues affords an air space between the grid and flues through which air may pass upwardly, and carry off the moisture evaporated from the material being dried, the moisture-laden air discharging from the apparatus through the passage 80 36.

The feature of providing the sloping grating in connection with the provision of the outlets at the lower portions of the walls of the receptacle 14 through which the gravel and other relatively large solid particles are permitted to discharge, but through which the wet sand will not pass, is of advantage 85 as it renders the structure self-cleaning, 90 which makes for efficiency and economy of operation.

The provision of the heat flue with the return bend, both portions of which are so positioned relative to the grating as to operate to dry the sand, is of advantage particularly because it permits of the utilization, to the maximum degree, of the heat supplied to the flues, while permitting the apparatus to be provided as a very compact 95 structure.

While I have illustrated and described a particular construction embodying my invention, I do not wish to be understood as intending to limit it thereto, as the same 100 may be variously modified and altered without departing from the spirit of my invention.

What I claim as new, and desire to secure by Letters Patent, is:

1. A drier comprising a member in the form of a grating extending in a substantially horizontal direction and sloping in a direction crosswise of its length and against which the material to be dried bears, and a heat flue extending lengthwise of said grating and having a wall spaced from and extending below said grating.

2. A drier comprising a member in the form of a grating extending in a substantially horizontal direction and sloping in a direction crosswise of its length and against which the material to be dried bears, and a heat flue extending lengthwise of said grating and having a wall spaced from, and extending below, said grating in substantially parallel relation thereto.

3. A drier comprising a member in the form of a grating extending in a substantially horizontal direction and sloping in a 130

- direction crosswise of its length and against which the material to be dried bears, and a heat flue extending lengthwise of said grating and having a sloping wall located adjacent to said grating and upon which the material drops from said grating. 5
4. A drier comprising a member in the form of a grating and against which the material to be dried bears, and a heat flue having a return portion with both portions of said flue extending in a position to heat the material bearing against said grating. 10
5. A drier comprising a member in the form of a grating and against which the material to be dried bears, and a heat flue having a return portion located above, and extending in the same general direction as, the other portion of said flue, said grating extending in such position relative to both 15 portions of said flue that the heat therefrom dries the material bearing against said grating. 20
6. A drier comprising a member in the form of a grating and against which the material to be dried bears, and a heat flue having a portion presenting a sloping wall and a return portion above the portion presenting the sloping wall, said grating extending above said sloping wall and adjacent said 25 return flue, for the purpose set forth. 30
7. A drier comprising a member presenting substantially horizontally extending upwardly-converging portions in the form of a grating and against which the material to be dried bears, and a heat flue extending lengthwise of said upwardly-converging portions and having upwardly converging walls located below, and spaced from, said upwardly-converging portions of said grating. 35
8. A drier comprising a member presenting upwardly-converging portions, and portions extending upwardly therefrom, in the form of a grating and against which the material to be dried bears, and a heat flue having a portion extending between and spaced from said upwardly-converging portions of said grating and another portion extending between the upwardly-extending 40 portions of said grating. 50
9. A drier comprising a member presenting upwardly-converging portions, and portions extending upwardly therefrom, in the form of a grating and against which the material to be dried bears, and a heat flue having a portion extending between and spaced from said upwardly-converging portions of said grating, said portion of said heat flue presenting upwardly-converging 55 walls and another portion extending between the upwardly-extending portions of said grating. 60
10. A drier comprising a receptacle for the material to be dried and having portions against which the material to be dried 65
- bears, said portions being in the form of a grating and converging upwardly, the walls of said receptacle adjacent the lower portions of said grating containing outlets for solid bodies, of a size too large to pass through said grating, a flue extending lengthwise of said grating and having upwardly-converging walls, said flue extending below and in spaced relation to said grating and having a return portion extending above the other portion of said flue and located between the portions of said grating. 70
11. A drier comprising a member presenting upwardly-converging portions, and portions extending upwardly therefrom, in the form of a grating and against which the material to be dried bears, and a heat flue having a portion extending between and spaced from said upwardly-converging portions of said grating and another portion extending between the upwardly-extending portions of said grating, said portions of said heat flue extending in non-vertical position. 75
12. A drier comprising a member presenting upwardly-converging portions, and portions extending upwardly therefrom, in the form of a grating and against which the material to be dried bears, and a heat flue having a portion extending between and spaced from said upwardly-converging portions of said grating, said portion of said heat flue presenting upwardly-converging walls and another portion extending between the upwardly-extending portions of said grating, said portions of said heat flue extending in non-vertical position. 80
13. A drier for the purpose set forth comprising a member in the form of a grating and against which the material to be dried bears, means for subjecting to heat the material bearing against said grating, and means for directing the hot dry sand which passes through said grating, and the gravel which is intercepted by said grating, into contact with each other while said sand is in heated condition. 85
14. A drier for the purpose set forth comprising a sloping member in the form of a grating and against which the material to be dried bears, means for subjecting to heat the material bearing against said grating, and means for directing the hot dry sand which passes through said grating, and the gravel which is intercepted by said grating, into contact with each other while said sand is in heated condition. 90
15. A drier for the purpose set forth comprising a member in the form of a grating and against which the material to be dried bears, means for subjecting to heat the material bearing against said grating, and means for causing the gravel intercepted by said grating to be fed continuously to, and for intermixture with, the hot dry sand. 95
- 100
- 105
- 110
- 115
- 120
- 125
- 130

16. A drier for the purpose set forth comprising a sloping member in the form of a grating and against which the material to be dried bears, means for subjecting to heat the material bearing against said grating, and means for causing the gravel intercepted by said grating to be fed continuously to, and for intermixture with, the hot dry sand.

17. A drier for the purpose set forth comprising a member in the form of a grating and against which the material to be dried bears, and means for subjecting to heat the material bearing against said grating, the drier having a closure-equipped portion through which the gravel intercepted by the grating discharges, said closure controlling the flow of that portion only of the material which is intercepted by said grating.

18. A drier for the purpose set forth comprising a sloping member in the form of a grating and against which the material to be dried bears, and means for subjecting to heat the material bearing against said grating,

the drier having a closure-equipped portion through which the gravel intercepted by the grating discharges, said closure controlling the flow of that portion only of the material which is intercepted by said grating.

19. A drier for the purpose set forth comprising a member in the form of a grating and against which the material to be dried bears, and means for subjecting to heat the material bearing against said grating, the drier being provided with a portion through which the gravel intercepted by the grating passes for discharge into the dry sand.

20. A drier for the purpose set forth comprising a sloping member in the form of a grating and against which the material to be dried bears, and means for subjecting to heat the material bearing against said grating, the drier being provided with a portion through which the gravel intercepted by the grating passes for discharge into the dry sand.

BARTON S. SNOW.
